PROCESS AND APPARATUS FOR REDUCING
WEAR AND TEAR IN INTERNAL COMBUSTION ENGINESWilly Neumann, Rollberg over Bernau, near
Berlin, GermanyApplication March 20, 1939, Serial No. 263,026
In Germany September 19, 1938

14 Claims. (Cl. 123—148)

The present invention relates to a process and an apparatus for reducing wear and tear in internal combustion engines in particular in modern automobiles, and an essential characteristic of the invention consists in that at definite intervals while continuously feeding fuel, the ignition is switched off for short periods. A further characteristic of the invention consists in that the switching off of the ignition does not occur simultaneously for all cylinders of the internal combustion engine but for each cylinder separately and thus for the cylinders in succession.

The apparatus for carrying out the process according to the invention is characterised in that in the ignition current circuit, a short circuiting apparatus is provided, which short circuits the ignition current circuit for each single cylinder at definite time intervals.

According to a further characteristic of the invention the ignition short circuit in the ignition circuit consists of a magnet bobbin and an iron core standing under spring tension and provided with a contact pin.

According to a further feature of the invention this short circuiter is arranged either at the distributor or at each sparking plug separately or at any other definite place in the ignition circuit.

By the invention it is ensured that the piston swept part of the idling cylinder and all bearings etc. are lubricated, and at the same time a cooling thereof is achieved.

The invention is more particularly described with reference to the accompanying drawings in which:

Fig. 1 shows a diagrammatic arrangement for carrying out the invention, in which the short circuiter is arranged at the ignition distributor.

Figure 2 shows also, and partly in section the arrangement of the short circuiter at the ignition current distributor.

Fig. 3 is a plan view of Figure 2.

Figs. 4 and 5 show partly in section and partly in elevation a device by means of which a short circuiter is provided over each sparking plug. In Fig. 4 it is shown in normal running position and in Fig. 5 with switched off or short circuited ignition.

In Fig. 1 is denoted by 1 a four cylinder block and by 2 the sparking plugs. These sparking plugs are connected by cable 3 with a current distributor of known type 4, and provided with current in such a manner that these current distributors feed the current in definite rotation to

the sparking plugs 2 one after another. At each distributor position 5 the distributor 4 is provided a short circuiter 6, which consists of a magnet spool 7 and an iron core 8. The iron core 8 with contact pin 9 stands under the action of a spring 10. The short circuiters 6 are fed with current from a source of current 11 of any kind through a contact device 12. This contact device consists of a disc 14 rotating on the shaft 13, which has a cam 15 on its circumference and corresponding to the four short circuiters 6, four contacts 16, 17. The feeding of the short circuiters 6 with the short circuit currents is brought about through the connections 18 from a source of current 11 to the resilient contact bows 16 and from the rigid contact pieces 17 through the connections 19. A switch 20 serves to switch in and out the short circuit apparatus. The drive of the shaft 13 of the contact device 12 can be brought about in any way for example from the motor shaft or by means of a special drive.

In normal action the switch 20 is opened, the short circuiting apparatus is thus without current and the sparking plugs 2 are fed in the usual manner through the distributor 4 with ignition current. If now the switch 20 is closed and simultaneously also the driving apparatus for the shaft 13 of the contact device 12 started then the short circuiters are fed with current through 18—16—17—19 at definite time intervals. Since the contacts 16, 17, are always open until closed by the disc 14 and then the corresponding short circuiter 6 is fed with current. In the drawing the contact 16, 17, denoted by a is closed directly by the action of cam 15 on the resilient contact bow 16 so that the short circuiter denoted by b is fed with current through the contact a the lead 18 and the lead 19. The exciting of the bobbin 7 of this short circuiter brings it about that the iron core 8 is drawn in against the action of the spring 10, and thereby the contact pin 9 is brought into contact with the corresponding distributor position 5, whereby a short circuiting of the sparking plug 2 corresponding to this position of the distributor is brought about. On the further movement of the cam disc 14 the cam 15 releases the bow 16, the corresponding contact is then again opened and therewith the short circuiting current interrupted until the cam 15 on the further movement of the disc 14 turns into the position of the next following contact bow in the direction of rotation, and then closes the contact, whereby the corresponding short circuiter 6 is subjected to current. The deprivation of the short circuiter 6 of current has for effect

that the iron core 8 with contact pin 9 by the tension of the spring 10 is drawn back again into the now currentless magnet bobbin 7, whereby the ignition current circuit of the sparking plug 2 concerned is again uninfluenced by the (short circuiting) current until the short circuit belonging to it is again put into function by the contact device 12. In this manner little by little in repeated cycles each sparking plug is again short circuited. During this short circuiting no ignition thus takes place in the cylinder concerned, while the fuel supply is normal, so that this cylinder during the short circuiting period idles. Thereby an improved lubrication of the bearing surfaces of the cylinder and of the bearings is produced and simultaneously the cylinder concerned can cool for a short period.

In Figs. 2 and 3 is shown a practical example of the constructive arrangement of the ignition current distributor with the short circuiting arrangement.

By 21 is denoted the usual distributor cap from which the sparking plugs are provided with ignition current. In the contact holes 22 of this distributor cap which otherwise serves for taking up the ignition current cable ends is inserted an intermediate plug 24 which on its side takes up the contact pins 26 of the ignition cables 3 in holes 25. Above the holes 25 for the ignition cables are holes 27 for carrying the short circuiters 6. These contain in a casing 28, the magnet bobbin and the iron core with contact pin 9 standing under the tension of the spring 10, which in the short circuit position of the short circuiter 6 in Fig. 1 contacts the contact pin 26 and thereby short circuits the ignition current. The connection for the lead of the short circuiting circuit at the magnet bobbin 7 is brought about through the contact screws 29.

The method of operation follows according to the explanation given of Fig. 1.

In Figs. 4 and 5 the arrangement is so chosen that above each sparking plug 2, a short circuiter is directly arranged. Each short circuiter 6 which corresponds in general to those described in Figs. 1-3, is mounted in a casing 20 which is carried by a standard 31 or the like fastened to the cylinder block, so that the contact pin 9 of the iron core 8 of the short circuiter stands over the sparking plug 2 which on its side carries an upwardly extending contact pin 32 cooperating with the contact pin 9.

The manner of action of this apparatus corresponds to that according to Figs. 1-3. If the magnet bobbin 7 is energised by the short circuiting current, it draws in the iron core 8, and this while overcoming the tension of the spring 10 makes contact with the contact pin 32 of the sparking plug 2 by means of a contact pin 9 which sparking plug is then short circuited (c. f. the position of the central pin 9 in Fig. 5), until again by interruption of the short circuiting current the magnet bobbin 7 becomes unenergised and thereby the iron core 8 is again moved back by the spring 10 into an inactive position so that the contact pin 9 is displaced from the sparking plug 2.

The invention is suitable for all kinds of internal combustion engines, in particular for aircraft engines.

I claim as my invention:

1. Method for reducing wear and tear in internal combustion engines, which consists in intermittently switching off the ignition for a short period, regardless of the speed of the engine,

while uninterruptedly maintaining the fuel supply.

2. Method for reducing wear and tear in internal combustion engines, which consists in intermittently switching off the ignition for a short period from one cylinder at a time regardless of the speed of the engine and while uninterruptedly maintaining the fuel supply.

10 3. A method of reducing wear and tear in multi-cylinder internal combustion engines consisting in intermittently and successively rendering in operation the ignition means associated with respective cylinders regardless of the speed of the engine and while uninterruptedly maintaining the fuel supply.

20 4. In the operation of a fluid pressure engine comprising a cylinder, a piston displaceable in said cylinder, means for providing an ignitable fuel-air mixture within the cylinder and electrical means for igniting said mixture, the process of preventing the operation of said igniting means for a short period of time regardless of the speed of the engine without discontinuing to introduce ignitable fuel-air mixture into the cylinder in order to prolong the life of said engine.

25 5. Apparatus for diminishing wear and tear in internal combustion engines, comprising a short circuiter in the ignition circuit which short circuits the ignition circuit for a definite period at definite intervals, a contact device, and a source of current for energizing said short circuiter through said contact device.

30 6. Apparatus for diminishing wear and tear in internal combustion engines comprising a contact device, a number of short circuiters each consisting of a magnet bobbin, a core slidable in said bobbin under the action of a spring and a contact pin on said core, said magnet bobbin being energized from a source of current through the contact device.

40 7. An apparatus for diminishing wear and tear in internal combustion engines comprising an ignition circuit distributor and short circuiters mounted on said distributor.

45 8. An apparatus for diminishing wear and tear in internal combustion engines comprising a short circuiter arranged above each spark plug of the said engine, each circuiter consists of a magnet bobbin, core slidable in said bobbin under the action of a spring, and a contact pin on said core.

50 9. An apparatus for diminishing wear and tear in internal combustion engines comprising a source of current a number of short circuiters, adapted to short circuit the ignition of said engine, connections between same and a switch device consisting of a cam disc adapted to be rotated by said engine and contacts adapted to be closed by said cam disc.

60 10. A fluid pressure engine comprising the combination with a cylinder, a piston displaceable in said cylinder, means for providing an ignitable fuel-air mixture within the cylinder and electrical means for igniting said mixture, of short circuiting means for intermittently rendering inoperative said igniting means for a definite period at definite intervals.

65 11. In a fluid pressure engine which comprises a cylinder, a piston displaceable in said cylinder, means for providing an ignitable fuel-air mixture within the cylinder and electrical means for igniting the mixture, the provision of short circuiting means for intermittently rendering inoperative said igniting means and means for short circuiting said ignition means for a definite period at definite intervals.

12. A fluid pressure engine comprising a plurality of cylinders, a piston displaceable in each one of said cylinders, means for providing an ignitable fuel-air mixture in each of the cylinders, electrical means for igniting said mixtures and means for intermittently rendering inoperative said igniting means by short circuiting said ignition means for definite intervals.

13. A fluid pressure engine comprising a plurality of cylinders, a plurality of pistons associated therewith, means for introducing ignitable fuel-air mixture successively into said cylinders,

5 electrical means for successively igniting the mixture in each cylinder and means for successively and intermittently rendering inoperative said igniting means by short circuiting said ignition means for definite intervals.

10 14. An engine according to claim 13, in which said means for successively and intermittently rendering inoperative the igniting means associated with each cylinder consists in a device for short circuiting said igniting means.

WILLY NEUMANN.
